UNITED STATES PATENT OFFICE.

LOUIS G. FREEMAN, OF CINCINNATI, OHIO, ASSIGNOR TO UNITED SHOE MACHINERY COMPANY, OF PATERSON, NEW JERSEY, A CORPORATION OF NEW JERSEY.

MACHINE FOR USE IN THE MANUFACTURE OF BOOTS AND SHOES.

1,113,114.

Specification of Letters Patent.

Patented Oct. 6, 1914.

Application filed October 18, 1909. Serial No. 523,144.

To all whom it may concern:

Be it known that I, LOUIS G. FREEMAN, a citizen of the United States, residing at Cincinnati, in the county of Hamilton and 5 State of Ohio, have invented certain Improvements in Machines for Use in the Manufacture of Boots and Shoes, of which the following description, in connection with the accompanying drawings, is a specification, like reference characters on the drawings indicating like parts in the several 10 figures.

This invention relates to the manufacture of boots and shoes and particularly to machines for working on welted shoes.

The invention will be explained in connection with the manufacture of Goodyear or welt shoes for which purpose the illustrated machine has been designed. In making welt shoes the upper is worked over the last in the lasting operation and at the heel the upper is permanently secured to the innersole by a row of fully driven heel seat tacks or other fastenings located along the 25 margin of the heel end of the shoe bottom. At the shank and forepart the overworked upper is secured by partially driven tacks and other temporary means in the lasting operation. These temporary fastenings are 30 later replaced by a seam which connects the upper and also a welt to the lip of the innersole. This seam, commonly called the "inseam", extends from a point adjacent to the heel seat on one side of the shoe along 35 the shank and forepart around the toe and to a point adjacent to the heel seat at the opposite side of the shoe. This seam, or the stitch forming instrumentalities employed in making it, tightens these portions 40 of the upper about the last and the seam fastens the upper snugly to the innersole. It is, however, impractical in forming this seam with the sewing machines used for the purpose to position the stitch-forming instrumentalities so that the seam is commenced 45 at the point where the permanent tacking of the heel seat ends or to continue the seam to the first fully driven tack adjacent to the end of the seam. At the latter 50 point the channel guide, which is located in advance of the stitch-forming devices and runs under or against the lip of the innersole, encounters the stock held by the first heel seat tack and thereby prevents the seam

from being continued beyond a point one-half inch or more from the first heel seat tack and there is usually about the same space at the other side of the shoe where the upper is not secured. Thus a place is left at each side of the shoe between the 60 inseam and the heel seat tacks where the upper is not snugly lasted over and fastened and a little looseness of the upper may usually be observed at these points after the 65 weltling operation. Also in many lasts there is an inward curvature of the last edge on one or both sides of the shoe at or adjacent to these points which requires, for the best fitting of the shoe, that a little extra 70 tightening of the upper be given at these places in order to conform the upper and heel stiffener to this contour of the last. In the heel attaching operation the heavy 75 pressure to which the shoe is subjected forces the upper materials outwardly at any points where they are not secured and then the fullness or looseness of the upper at 80 the front end of the heel seat is more obvious and it detracts from the appearance of the shoe. Another condition which contributes to this looseness is that the ends of the inseam, particularly the final end, usually run up toward the top or edge of the lip instead of being formed in the channel at the base of the lip. This is because the 85 overdrawn and tacked upper at the heel seat renders it difficult for the sewing machine operator to position the sewing instrumentalities down in the channel, or against the base of the lip, in starting the 90 seam and to retain them there as the sewing approaches the tacked heel seat on the side where the seam is ended. In those shoes in which the lip is formed by two flaps turned up toward each other the seam near 95 its end sometimes includes only the outer flap because of the difficulty in keeping the stitch-forming devices down to the base of the lip. The portion of the seam which runs up toward the top of the lip is forced outwardly by whatever tension there is on the upper and also by reason of the bending of the lip under the pressure of the heel attaching operation so that the looseness produced 100 in the upper extends forwardly along the rear end portions of the inseam as well as being found in the space between the inseam and the heel seat tacks. To tighten these 105

loose portions of the upper materials of a
welt shoe over the last and secure them is
of course in the nature of a portion of the
lasting operation but is a part of that opera-
5 tion which is necessarily deferred until
after the welt attaching operation.

In the recent development of shoe manu-
facturing there has been, as is well known,
a demand on the one hand for better fitted
10 shoes and on the other hand for expedition
and economy in the several making opera-
tions. An effort has been made to meet the
first demand by employing a workman to
press or rub with his thumb the shoe stock
15 at and adjacent to the end of the inseam
upwardly and inwardly over the edge of the
shoe and hold it while he drives a tack to
secure it in tightened relation to the last.
This manual operation has been a rather in-
20 effective and a slow one and the demand for
expedition and economy of labor has made
this hand operation practical only on the
higher priced shoes. A machine designed
to replace this hand operation for tight-
25 ening and securing the upper materials over
the last at the ends of the inseam so as to
do the work more effectively than the hand
workman and at such small cost as to per-
mit its use on cheap welt shoes as well as
30 upon the higher grades, forms the subject-
matter of my co-pending application Serial
No. 717,612, filed August 28, 1912.

The machine above referred to is adapted
35 to operate upon a shoe having the forward
portion, shank, and heel seat lasted and a
welt attached to the upper and innersole
about the forward portion and shank, and
comprises means for engaging the shoe stock
40 for a limited distance adjacent to the rear
end of the welt to tighten the upper about
the last and hold the upper while it is be-
ing secured.

The machine further comprises mecha-
45 nism for driving tacks to effect the secur-
ing of the upper. The engaging means is
preferably constructed and arranged to con-
tact with the shoe stock in the crease be-
tween the upper and the welt, usually called
50 the "welt crease", and by such engagement
at and adjacent to the end of the inseam to
crowd the upper over the edge of the last
and the innersole. Force applied to the
shoe at this point can be made to draw
55 snugly to the last the portion of upper in-
tervening between the end of the seam and
the end of the row of heel seat tacks as well
as the portion of upper immediately adja-
cent to or below the end portions of the in-
60 seam. Preferably the tack driving means is
arranged in proximity to the engaging
means, and the tacker and engaging means
may be arranged for relative movement in
a direction to bring the tacker and the en-
65 gaging means from a relative position suit-
able to permit the convenient engagement

of said means with the shoe into a different
position for the securing tack to be driven
in the desired place. As therein shown the
70 shoe and the engaging means are movable
together toward and from the tacker and
the latter may include suitable starting and
stopping means controlled by a foot treadle
or otherwise.

The ends of the welt are not left by the
welt attaching operation in suitable beveled
75 condition to form with the rand or the seat
end of the heel the desired lap joint and re-
quire therefore to be beveled or scarfed for
this purpose. This welt end beveling opera-
tion, called "welt butting" in the shop, is
80 at the present time done by hand. An im-
portant feature of the invention of said co-
pending application consists in the provision
of a single machine constructed and ar-
ranged to perform the two operations here-
85 fore done by hand, of butting the welt and
tightening the upper and securing the upper
material, including, it may be, the welt, in
proper relation to the last and to other parts
of the shoe.

In the machine above referred to a welt
supporting means is provided which is
adapted to extend under the welt between
it and the shoe bottom to guard the shoe
from the welt butting knife and to protect
90 the knife from engagement with the heel
seat tacks. This welt supporter is formed
and arranged to hold the end portion of the
welt in proper angular relation to the path
of the cutter to secure the desired form of
100 bevel on the welt end both lengthwise and
transversely of the welt. The machine is
provided with means for beveling the two
ends of the welt at the same time at opposite
105 sides of the shoe and the welt positioning
means includes devices arranged to support
the two welt ends in planes inclined trans-
versely of the shoe to each other and to the
plane of the shoe bottom. This arrange-
110 ment, in addition to determining the pos-
ition of the welt ends provides a formation
adapted to receive the transversely arched
or peaked shank with which some shoes are
formed. The welt rests extend between the
115 lower face of the welt and the tacked heel
seat of the shoe and are provided with for-
wardly extended guides or fingers to en-
gage the relatively smooth middle portion
of the shoe bottom and direct the rests into
120 their operative relations to the work. In
the machine of the present invention, which
is an improvement upon the machine above
referred to, the rests, preferably, have sharp-
ened front ends which form stitch cutting
125 edges to sever the inseam stitches in case
the inseam is extended too far toward the
heel on either side of the shoe. An adjust-
able back stop or heel end rest is provided to
control the distance from the heel end of
130 the shoe at which the stitches shall be cut

and the welt ends butted. The stitch cutters are mounted to yield independently to permit either one of them to give way to an unusual obstruction and permit the shoe to be positioned against the back stop in the right relation to the welt butting knives. The welt rests are mounted to occupy normally a shoe receiving position below the welt butting position so as to facilitate the 10 positioning of the shoe.

The stitch cutting is or may be effected before the shoe reaches the welt butting position. The upward movement of the welt rests and the shoe to welt butting position may advantageously be effected by or as an incident of the backward movement of the shoe against the stitch cutting edges and against the back stop. To this end said rests which comprise also the guide 15 fingers, the shoe guards and the stitch cutters are mounted for movement obliquely upwardly and backwardly by rearward pressure of the shoe, said parts as shown being supported upon parallel links by which this 20 movement and that of the shoe is directed and controlled.

In accordance with another feature of this invention the welt butting knives become operatively connected with their actuating 30 mechanism during or as an incident to the backward movement or pressure of the shoe against the welt resting and stitch cutting devices and the back stop. This provides an arrangement very convenient for the operator who guides the shoe to proper 35 relation to the welt rests by a backward movement under the guiding fingers, then presses backwardly to cut the stitches to proper points determined by the back stop, then 40 continues the movement by which the shoe and rests are forced backwardly and upwardly into the field of operation of the welt butters and in this movement automatically starts the welt butters into operation to 45 remove the surplus material from and to shape the ends of the welt. It will be observed that the stitch cutters operate in one position of the shoe and the welt butters in a different position of the shoe but both act 50 while the operator maintains his manipulative hold upon the shoe as do also the upper tightening and tacking instrumentalities which do their work in still another position of the shoe.

55 A further feature of this invention comprises novel means for rubbing or smoothing down the welt end in advance of the welt butting knife so as to present the welt end in the proper position for the cutting operation.

These and other features of the invention, including certain details of construction and combinations of parts, will be further explained in the following description 65 and then pointed out in the claims.

The drawings represent an apparatus embodying the invention in the best form now known to me.

Figure 1 shows in side elevation the head of the machine; Fig. 2 the head of the machine and the jack in front elevation; Figs. 2^a, 2^b, 2^c are respectively top, front and side views of the upper portion of the jack spindle; Fig. 3 shows in plan and in operative relation to the shoe the welt resting and stitch cutting devices, the welt butting devices, and the shoe engaging member by which the upper is tightened over the last adjacent to the end of the welt and held in position to be fastened by the tacker which appears in section. The operative movements of the shoe for presenting it to each of these devices successively are indicated by arrowheaded lines; Fig. 4 is a side elevation and sectional view on the line 4—4 of Fig. 3 showing the upper tightening device in operative relation to the shoe and disclosing the bent formation of that device by reason of which inward pressure of the shoe automatically effects an upward movement of the shoe into operative relation to the tacker nozzle; Fig. 5 is a plan view to show particularly the members for cutting the stitches and supporting the welt ends in position for the operation of the butting knives in beveling the welt. This figure discloses the transverse relation of the guide fingers of said member to the shoe; the arrangement which permits said members to yield independently; and the 100 adjusting means for the hold back stop; Fig. 6 is a side elevation showing the operative relation of a welt supporting and stitch cutting member to the shoe, the end of the welt to be butted off and the angle 105 of the bevel being indicated by dotted lines, and Fig. 7 shows in vertical section the lower portion of the jack including its locking and uplifting mechanism.

The machine comprises a column 1 on 110 which is the head 2 having two brackets 3 and 4. The bracket 3 at the right hand side, Figs. 1 and 2, has two parallel arms 22, 23 which project upwardly and forwardly and between which is hung on a pivot 26 a swinging block having depending arms 24, 25 which flare outwardly, see Fig. 3, and carry the welt butting knives 27 which are set obliquely as shown in Figs. 2 and 1 with relation to the vertical transverse and longitudinal planes of the machine. Coöperating with these knives and supporting the welt ends for the action thereof are welt rests 28, 29 also arranged, Fig. 2, in oppositely inclined relation to the vertical longitudinal plane of the machine. This adapts them to receive beneath them and guard from injury by the knives a shoe having a rounded or peaked shank and to support the welt ends in their usual outwardly inclined relation to 125 130

the shoe. The front ends of the welt rests are sloped as indicated at 30, Figs. 5 and 6, to position the portion 32 of the welt 33 to be cut off in suitable angular relation to the 5 path of the knives for producing the desired bevel or scarf. The front edges of these welt rests are sharp enough to cut any 10 stitches of the inseam which extend too far back on the shoe. The welt rests have forwardly extended fingers 31 to form guides for assisting the operator in presenting the shoe in operative relation to the welt rests and the stitch cutting edges thereof. These 15 fingers are located to engage the relatively smooth middle portion of the shoe bottom or innersole so that the operator can slide the shoe backwardly in contact therewith. The pivot 26 for the knife block is located, Fig. 1, substantially over the place where the 20 welt cutting is to be done so that the butting knives, while cutting, move in a plane substantially parallel with the shoe bottom and the bevel formed on the welt ends is thus determined by the bevel 30 of the welt 25 rests. The knife block supports yielding wipers, shown as formed by loops 35 of spring wire, adapted to rub over the welt end immediately in advance of the knives and hold the portion to be cut down upon 30 the welt rests so that the welt end cannot curl up and cause a sharper bevel or scarf to be formed than that for which the machine is arranged. The yielding nature of the wiper 35 permits it to move relatively to 35 the knife while rubbing over the surface of the welt as the knife cuts obliquely through the welt in forming the bevel or scarf on the welt butt. The term "knife" as applied to the welt butting device of this invention is 40 to be understood in this specification and in the claims, where the context and the state of the art permit, as a term of designation, and not one of limitation, to mean any suitable device for removing the surplus material 45 from the end portion of the welt.

The welt rests 28, 29 are plates formed as shown best in Fig. 5 and carried in a frame 38 in which they may be arranged for limited longitudinal movement independently 50 against the tension of springs 36 which are connected thereto and to studs 37 projecting from the frame through slots 39 in the rests. This permits either rest, if it strikes an unusual obstruction, such as a nail, 55 to yield and permit the proper presentation of the shoe to the welt butting knives which in such instances can be relied upon to sever the surplus material from the shoe without too great danger of injuring the shoe by 60 reason of the absence of one welt rest from its proper position. The studs 37 may comprise headed clamping screws which can be set down as in Fig. 6 to secure the welt rests in different adjusted relations to the knives 65 and to other parts of the machine.

The frame 38 is movably mounted on the upper ends of parallel links 42, 43 connecting it with the bracket 3 at 40, 44 and 41, 45 respectively, Figs. 1 and 3, and a spring 46 holds the frame normally forwardly with 70 the links tilted as shown in Fig. 1 whereby the frame and the welt rests are lowered as well as forwardly projected. The extent of this movement is limited by an adjustable stop screw 47 which is shown in dotted lines. 75 This arrangement presents the welt rests in a shoe receiving position below and in advance of the welt butting position where the operator can conveniently slide the shoe backwardly in contact with the guide fingers 80 31 until the stitches of the inseam strike the stitch cutting edges of the welt rests if the seam has been extended backwardly too far on either side of the shoe. The backward movement of the shoe will in such case be 85 continued until the stitches are cut to the points at each side of the shoe for which the machine is set. This is determined in part by the position or adjustment of the rests and finally by a back stop 48 arranged in 90 the frame 38 to be engaged by the heel end of the shoe, Fig. 5. This pressure of the shoe backwardly against the stitch cutters or the back stop, or both, is made to overcome the tension of spring 46 and move the 95 frame 38 and the welt rests backwardly and upwardly by the rearward swinging of links 42, 43 with the shoe guided and controlled as to position, both longitudinally and vertically, by the back stop and the welt rests. 100 The extent of this movement of the frame 38 and parts associated with it is limited by an abutment 51 Figs. 1 and 3. The back stop 48 is arranged for adjustment by a rack 105 49 and hand wheel 50 for different sizes of shoes and the hand wheel has suitable graduations indicated on it as shown in Fig. 5.

A trigger 53 is pivoted to the frame 38 at 52 for endwise movement therewith against the arm 54, Fig. 1, of a clutch controller in the form of a bell crank, the other arm 55 of which has a detent 56 to engage a lug 57 of a one revolution clutch 58 which may be of any suitable type and is not necessary to describe here. Power is derived from the shaft 11 through a belt 59 on a loose pulley 60 on the clutch shaft 61. The shaft 61 carries an eccentric 62 embraced by a strap on a rod 63 which extends forwardly to the swinging knife block to which it is connected at 64 for swinging the welt butting knives about the pivot 26. The normal position of the clutch controller 54, 55, which is pivoted at 65 is that shown in Fig. 1 in which it is held by the spring 67 and an adjustable stop 66. The trigger 53 has an inclined shoulder 70 in the path of which is an abutment 69 on a post 68 and this abutment lifts the trigger in the last 125 130

portion of the backward stroke of the frame 38. This arrangement provides that the actuating means for the welt butting knives shall be started during the movement of the 5 shoe (and the frame 38) from position of presentation to welt butting position by the withdrawal of the clutch controller from the lug 57 and that the trigger shall release the clutch controller and permit it to 10 return to position to stop the actuating mechanism at the end of a single revolution of the shaft. The provision for lifting the trigger during the last part of the movement of the shoe into operative relation to the 15 welt butters insures that the machine shall not repeat its operation if the shoe is not promptly withdrawn after the welt butting operation.

The upper tightening and securing mechanism to which it is contemplated that the shoe will be presented after the welt ends have been butted, is mounted on the second bracket 4 of the machine, Fig. 1, and includes the plate or blade 5 which is adjustably, but stationarily, attached by bolt and slot connections, Fig. 3, to the bracket 4 so as to permit it to be positioned at the desired distance laterally from the nozzle 7 of the tacker to permit the convenient introduction of the welt between the blade and nozzle and also the driving of the tack from the nozzle at the desired distance inwardly with relation to the inseam. The blade 5 has an edge formation to adapt it 30 to enter the welt crease, between the welt and the upper of the welted shoe, and preferably is thin enough to bear upon the stitches of the inseam or the stock adjacent to the stitches for pressing the stock inwardly to tighten the upper as the shoe is 35 pressed laterally against the end of the blade. The end portion of the blade is located below the nozzle a sufficient distance to facilitate the presentation of the 40 shoe conveniently against the blade as above described and the manipulation of the shoe to stretch or tighten the upper over the last for removing any slack or looseness which may exist and conforming the upper 45 materials to the contour of the adjacent portion of the last. The blade 5 is preferably of spring metal and has between its operating end and its attaching end an upward bend so that the outer end is located in 50 a higher plane than the inner end and has a tendency to spring upwardly when pressure of the shoe laterally is applied thereto. This causes the shoe engaging end of the blade to move automatically, and carry the shoe 55 with it, upwardly toward the plane of the nozzle, and into engagement with the nozzle, during the upper tightening operation whereby the shoe is presented in proper position for the tacking operation while the 60 upper is held in position to be secured and

without special attention from the operator. The shoe engaging end of the blade 5, while being formed to engage the shoe for a limited distance only adjacent to the end of the inseam and the row of heel seat tacks, 70 is preferably of substantial width, as shown, to engage several stitches, so as not to strain the inseam too much, and to overlie and rub against the upper in the space between the stitches and heel seat tacks. 75 This allows also that the shoe may be turned in a horizontal plane to apply extra pressure at the end of the inseam, and rub along the upper in said space for working the upper into proper lasted position and 80 if desired bending or inclining the end portion of the welt inwardly. When the upper has been properly tightened by the manipulation of the shoe against the blade 5, the tacker is caused to insert a tack by 85 depressing a treadle connected with the treadle rod 14, Figs. 1 and 2. This tacker may be of any suitable construction, such for example as that shown in United States Letters Patent to Pym, No. 763,927, and as 90 no claim is made herein to the construction of the tacker it will not be described in detail, and it will be sufficient to mention that it comprises a driver 6 working in the nozzle 7 and operated by a lever 8 pivoted at 95 9 and lifted against the spring 15 by a cam 10 of the shaft 11 which is driven by a pulley 12 and controlled by a clutch 13 to which the treadle rod extends. The tacks are fed to the nozzle from a hopper 16 in 100 which is tack feeding mechanism driven by gears 17 and 18, pulleys 19 and 20 and a belt 21 from the shaft 11.

The stitch cutting means, the welt butting means, the upper tightening means and the tacking means are arranged relatively to facilitate the presentation of the shoe to one after another conveniently and rapidly and all while the operator maintains his manipulative hold upon the shoe. A shoe support is provided for use if desired in presenting the shoe to each of these means which operate on the shoe although the shoe may be supported entirely in the hands of the operator. The shoe support comprises 110 a jack pin 71 pivoted at 72 to have limited swinging movement in the sleeved upper end of the jack post 73, which in turn is supported at its lower end by a ball and socket joint 74, see Figs. 2 and 7, in the upper end of a sleeve 75 arranged to telescope in a surrounding cup-shaped sleeve or support 76, being yieldingly supported therein by a spring 77. The supporting sleeve 76 is formed integrally with an arm 78 fast on a shaft 79 pivoted on a block 80 mounted on the front of the column so as to bring the jack near to and approximately beneath the tacking mechanism. The shaft 79 is provided at its outer end, see Fig. 2, 130

with a rearwardly extending crank 81, see also Fig. 7, connected by a rod 82 to an eccentric 83 driven by the shaft 11 whenever the clutch 13 is released by the operator. 5 Pivoted at 84 to the jack support 78 is a locking dog or lever 85 whose lower end 86 when in the position shown in Fig. 7 permits the sleeve 75 to move freely up and down in the sleeve 76, but when turned in 10 its pivot away from the position shown in Fig. 7 it instantly bites against the wear plate 87 and locks the two sleeves immovably together. To accomplish the automatic locking of the jack as thus explained the 15 upper end of the lever 85 is provided with a bearing surface 88 to engage the cam end 89 of a block 90 adjustably secured by bolts 91 to the upper end 92 of the block 80. The action of this cam arrangement is such 20 that when the jack is raised by the rod 82 to bring the shoe into position beneath the tacker, the jack is positively locked against yielding movement just as it gets into nail-receiving position with the leather against 25 the bottom of the nozzle 7, the rod 82 giving a very slight further upward movement to the jack, with the result that the leather is pinched against the last as the tack is driven, with almost exactly the same action 30 and result as when a nail is driven by a hand hammer. The forcible pressing together of the jack and nozzle acts like a hammer to pound the leather as the tack is driven.

35 The operation of the machine is as follows. The operator first seizes the jack post 73 and swings it forward into jacking position, places the shoe on the spindle 71 and then sliding it under the guide fingers 31 and 40 working the welt ends over the welt rests, swings it to the right and back with the heel toward the machine until the heel rests against the heel stop 48, and the beveled edges of the angularly arranged 45 welt rests 28, 29 extend over the bottom of the heel-part of the shoe and between the seam and the ends of the welt in the position shown in Fig. 6. If there are any inseam stitches to cut they are severed as the shoe 50 is forced back against the back stop, the operator then forces the shoe inwardly in the direction of the arrow 93, Fig. 3, until the clutch trip 56 releases the clutch 58. By this time the shoe and its welt-supporting 55 rests 28, 29 have been swung on the links 42, 43 rearwardly and upwardly toward the full line position, Fig. 1, so that the top surfaces of the members 28, 29 are in the proper plane of coöperate with the scurfing knives 60 27. Immediately upon the releasing of the clutch 58, the knife actuator 63 is moved to the rear, thereby swinging the scurfing knives downwardly in an arc of movement approximately tangential to the top surfaces 65 of the parts 31 and slicing or chopping off

the welt ends with a bevel or length of slope regulated by the angle or bevel of the surfaces 30. The smoothing wires 35 straighten and rub the welt down flat ahead of the knives, so that an even, accurate cut is made. 70 Adjustment of the heel stop which engages the rear end of the heel determines the point where the welt shall be butted or its distance from the rear end of the shoe, and the scurfing takes place instantly when the shoe has 75 been pushed back to proper position. Simply pushing the shoe back into position as far as it will go automatically throws in the clutch which operates the cutting mechanism. As soon as the welt is trimmed or 80 scurfed the knife returns to raised position and the shoe is then pulled forward toward the operator and swung around in the direction of the arrow 94, the adjacent front edge and corner of the blade 5 being located conveniently to catch under the welt as soon as the shoe is swung toward it and then, as the shoe is moved forward so as to bring the adjacent scurfed end of the welt below the nozzle, the stationary blade 5 engages the stitches 95 which join the welt to the shoe upper; and the operator, by pressing inwardly on the shoe, stretches the slack leather of the upper tightly over the last, and, as he does so, depresses the treadle 90 rod 14, causing the jack to be at once raised and then automatically locked by the engagement of the surfaces 88, 89, and then the further raising movement hammers or 95 pinches and presses the welt down hard upon the upper, and at the same moment the nail is driven by the nailer or tacker. 100

The operator has been enabled to retain his grasp of the shoe so that as a result of the combined hand manipulation and machine manipulation a smooth, tight shank portion of the upper is secured. After one side is nailed the jack-locking mechanism releases and permits the lowering of the jack, and the operator pulls the shoe toward him from 105 under the nozzle, turns the shoe and presents the other side, pressing the upper and welt against the pusher blade 5 to tighten the upper on the second side and again depresses the treadle and treadle rod 14, causing the jack to rise, become positively locked and then hammer or press the stock hard against the nozzle (which I make extra large for facilitating this operation) and drive the nail, thereby holding all that the 110 hand manipulation and juxtaposition of mechanisms have accomplished. When a nail is driven and the machine comes to the stopping point, the jack is thereby released so that the operator can pull the shoe toward him for inspection or can swing it on the comparatively long front edge of the presser 5 or otherwise manipulate the leather so as to pull or wipe the stock into the desired position for receiving another 115 120 125 130

tack if deemed necessary. The jack is operated in timed relation with the tacking mechanism and only when a nail is being driven, being free to yield at all other times 5 and adjust itself according to the thickness of the last and shoe. The jack does not lock excepting on the last quarter of its upper stroke, and is even then capable of slipping under pressure which would injure the 10 work, being entirely free approximately three quarters of the stroke, depending upon the adjustment of the cam block 90, but when butting the welt the jack is perfectly free and it is also perfectly free when placing the shoe on the jack spindle, and when moving the latter under the nozzle to tack the joint. It is not locked until the operator depresses the treadle to drive the nail, which starts the jack lever 81 to swing the 15 locking device upward, although, in practice, this does not usually move the jack, which has already been previously so shifted as to bring the leather of the shoe against the nozzle. As soon as the jack lever has 20 brought the locking mechanism into action, then the further movement of said lever starts the compression of the leather between the jack spindle and the nozzle, this pressure being exerted on the loose leather 25 under the nozzle where the tack is to be driven. For handling the average sizes of adult shoes, the presser 5 and the tacker are about four inches forward of the mechanism 30 for butting the welt and about three inches to one side, this relation of the parts permitting the operator to maintain his grasp 35 upon the leather about the waist of the shoe while moving the shoe in the directions of the arrows 93, 94, and this relation also 40 causes the adjacent corner or edge of the blade 5 to engage between the welt and upper when the shoe is swung as indicated by the arrow 94. The engaging end of the 45 blade 5 is located immediately below and approximately in line with the tack delivering end of the nozzle 7 in position to press against the adjacent line of stitches. The operator catches the welt over said positioning end of the blade so as to bring the edge 50 of the latter against the line of stitches, and in this position the shoe is pressed gently and yet quickly forward to stretch the upper tight against the last and take up all loose leather. One purpose of having a wide end 55 to the blade is so that it may wipe or smooth forward all the loose leather and hold this previously defective spot in properly stretched position while the holding tack or tacks are being driven. The main pushing 60 or stretching is done by the part of said end which is toward the toe of the shoe, so that the right hand part does the main pushing or stretching for one side of the shoe, and the left hand part for the other side of the 65 shoe. The operator simply engages the

blade between the welt and upper and pushes straight in and the spring of the blade, pusher, or positioner, permits the operator to get the shoe in exactly the position desired under the nozzle at the same time 70 that he is stretching the upper by the forward pushing movement. The shoe is first engaged by the blade 5 and then, after or during the stretching of the shoe, is engaged on the shoe bottom by the nozzle 7. The 75 upper tightening member indicated at 5 is shown and sometimes referred to herein as a blade and while this member may, with certain advantages, be formed as a thin plate, the term is used as one of designation 80 and not as a term of limitation and wherever the context and the art permit it is to be construed broadly as a member of any suitable form capable of performing the tightening operation. 85

Having explained the nature of this invention and fully described a construction embodying the same and how it may be used, I claim as new and desire to secure by Letters Patent of the United States:— 90

1. In an apparatus for use in removing surplus material at and adjacent to the two end portions of the welt of a lasted and welted shoe, welt end rests comprising side members inclined transversely of the shoe in opposite directions and having sharpened inseam stitch cutting edges extending transversely of the shoe. 95

2. A welt butting machine having, in combination, means for removing surplus material at and adjacent to the two end portions of the welt and inseam stitch cutting means comprising oppositely inclined members formed to receive an arched shank between them and having sharpened stitch cutting ends extending transversely of the shoe. 100

3. A welt butting machine having, in combination, means for removing surplus material at and adjacent to the two end portions of the welt, welt rests having stitch cutting front edges and a guard extending forwardly of said edges. 110

4. A welt butting machine having, in combination, means for removing surplus material at and adjacent to an end portion of the welt, a separate stitch cutter, and a guard extending in advance of the stitch cutter. 115

5. In a welt butting apparatus an inseam stitch cutter and a shoe guide and guard arranged to engage the shoe bottom at the inner side of the inseam and permit the shoe to slide therealong into operative relation to the stitch cutter. 120

6. In a machine of the class described, a stitch cutter having a guard extending in advance thereof and adapted to form the initial contacting point between the shoe bottom and the machine. 125

7. In a welt butting machine, a stitch cut- 130

ter mounted for movement upwardly from a shoe receiving position to position for the welt to be butted and having a non-cutting guard extending in advance of the cutting edge and arranged to facilitate the positioning of the shoe.

8. In a welt butting machine, a welt butter, and a stitch cutter mounted for movement upwardly and backwardly from shoe receiving position while maintaining constant angular relation to the horizontal.

9. In a welt butting machine a stitch cutter arranged to act lengthwise of the inseam and provided with a guard extending in advance of the cutting edge and adapted to engage the innersole at the inner side of the inseam.

10. In a welt butting machine a stitch cutter arranged to permit the shoe to be pressed backwardly against it for cutting the stitches, said cutter being mounted for movement upwardly by such pressure of the shoe whereby to avoid cutting too deeply into the shoe bottom.

11. In a welt butting machine, stitch cutters for the opposite ends of the inseam arranged to permit the shoe to be pressed backwardly against them, and means for automatically raising the cutters during said backward pressure.

12. A welt butting machine, having in combination, a welt butter, a welt rest having a stitch cutting edge, a stop for limiting relative movement of the shoe and rest, and actuating means for the welt butter arranged to be started by movement of the rest and shoe together after the stitches have been cut.

13. A welt butting machine, having in combination, means for removing surplus material at and adjacent to the ends of the welt, stitch cutters, a stop, a movable support for the stop and cutters, and connecting mechanism wherethrough movement of said support causes said means to do its work.

14. A welt butting machine, having in combination, a welt butter, a stitch cutter, a support for the stitch cutter adapted for movement by the shoe to cause the welt butter to do its work, and a contact member adjustable to determine the point to which the stitches can be cut before the welt butter is caused to operate.

15. In a welt butting apparatus, resting and positioning devices arranged to be inserted under the two butt end portions of the welt by a relative movement of the shoe and said devices lengthwise of the shoe, said resting devices having welt supporting faces oppositely inclined to the vertical longitudinal plane of the apparatus in combination with welt butting knives movable over said devices to bevel the welt ends, and means for pressing the welt ends down upon said devices in advance of the operation of the knives.

16. A welt butting apparatus, having in combination, a welt rest, a swinging butting knife to bevel the welt, and a yielding wiper arranged to rub over the welt in advance of the knife and yield relatively thereto as the knife cuts into the welt in forming the bevel.

17. A welt butting apparatus, having in combination, a knife, means to actuate the knife in an arc to butt the welt, a welt rest formed to support the welt end in an inclined position in the path of the knife to determine the bevel at which the welt shall be butted, and means for securing the rest in different adjusted positions longitudinally of the path of the knife.

18. A welt butting apparatus, having in combination, a butting knife, an inseam stitch cutter, and means whereby the said knife and cutter can be adjusted relatively.

19. A welt butting apparatus, having in combination, butting knives and welt rests for opposite sides of the shoe and mountings for the rests to permit independent endwise yielding movement of either rest.

20. A welt butting machine, having in combination, a stitch cutter, a welt butter and a tacker arranged to act on a shoe in different positions of the shoe, and a shoe support constructed and arranged to support the shoe in said different operative positions.

21. A welt butting machine, having in combination, a welt butter, actuating mechanism therefor including a clutch, a stitch cutter with relation to which the shoe may be positioned before it is presented to the welt butter, and means arranged to trip the clutch automatically during movement of the shoe to the welt butter.

22. A machine of the class described, having in combination, a device for operating on a shoe, actuating mechanism therefor including a clutch, a second device for also operating on the shoe and with relation to which the shoe must be positioned before it can get into the field of operation of the first mentioned operating device, and means arranged to trip the clutch automatically during subsequent movement of the shoe to the said first mentioned operating device.

23. A machine of the class described, having in combination, means to skive a welt end, means to rub the welt end down in advance of the skiving means, means to compress the stock against the last bottom and means to insert a tack to secure the stock.

24. A machine of the class described, having in combination, means to skive a welt end, means to rub the welt end down in advance of the skiving means, means to press the shoe stock inwardly adjacent to the welt end, means to compress the stock against the last bottom, and means to insert a tack to secure the stock.

25. A machine of the class described, hav-

ing in combination, stitch cutting means and welt butting means arranged to operate on a shoe in one position, and upper tightening means and tacking means arranged to operate on the shoe when the shoe has been moved to a different position.

26. A machine of the class described, having in combination, stitch cutting means, welt butting means, welt butt holding down means, upper tightening means, and tacking means, said tightening and tacking means being arranged laterally adjacent to the other means to operate on a shoe which is presented thereto in a different position from that in which the shoe is presented to said other means.

27. A machine of the class described, having in combination, stitch cutting means, welt butting means, automatic starting means for the butting means, upper tightening means, and tacking means.

28. A machine of the class described, having in combination, stitch cutting means and welt butting means, together with upper tightening means, stock compressing means, and tacking means, which latter three means are arranged for operation upon a shoe when the latter has been moved away from the cutting means and has been repositioned against the tightening means.

29. A machine of the class described, hav-

ing, in combination, a cutter to sever the inseam stitches, a blade to tighten the upper, and a tacker to fasten the upper, said members being arranged adjacent to one another to facilitate presentation of the shoe to them successively.

30. A machine of the class described, having, in combination, a cutter to sever the inseam stitches, a cutter to butt the welt, and a tacker to fasten the welt end, said members being arranged to require movement of the shoe against the stitch cutter into operative relation to the welt butter and to require a relative movement of the shoe and the tacker into co-operative relation after the welt ends have been butted.

31. A machine of the class described, having, in combination, a cutter to sever the inseam stitches, a cutter to butt the welt, a blade to tighten the upper, a tacker to fasten the upper, and a support for the shoe by which it is movable to present the same shoe in different positions to said cutters, blade and tacker successively.

In testimony whereof I have signed my name to this specification in the presence of two subscribing witnesses.

LOUIS G. FREEMAN.
